UNITED STATES PATENT OFFICE.

GEORGE BICK, OF CHICAGO, ILLINOIS.

CARPENTER'S SQUARE.

1,236,817.

Specification of Letters Patent. Patented Aug. 14, 1917.

Application filed August 30, 1916. Serial No. 117,580.

To all whom it may concern:

Be it known that I, GEORGE BICK, a citizen of the United States, residing at Chicago, in the county of Cook and State of Illinois, have invented certain new and useful Improvements in Carpenters' Squares, of which the following is a specification.

This invention relates to carpenters' squares, which have impressed on their flat faces tables of calculations furnishing data to enable a carpenter or builder to easily and quickly ascertain the lengths of various kinds of rafters and braces, and to obtain other information concerning the same when the pitch and span of a roof or similar structure are known.

The principal aim in providing tabulated squares of this character is to facilitate the work of a builder. It has been found, however, that the majority of squares heretofore provided are crowded with tables and data which are unnecessary and are never referred to by the ordinary builder. Such tabulations tend to confuse and render the square valueless for the very purpose for which it was designed. For example, carpenters' squares will be found to contain tables relative to board measure, brace measure, octagon, polygon and special angle cuts, and other indicia which enable one to ascertain the lengths and cuts of rafters of various classes such as common, hip and valley, cripple rafters, etc. When complications of this diversified character are crowded onto the faces of a square, it will be evident that the usefulness is materially, if not wholly, subverted by their complexity, since the ordinary carpenter is confused by the complexity of the data and cannot spend the time necessary to search out of such an array of figures only certain information that he has occasion to refer to very frequently in the ordinary course of his work.

The primary object of my invention is to provide a carpenter's square, tabulated in such simple and novel manner as to effectively and practically serve the needs of a carpenter or builder in ordinary construction work. I have aimed to provide a tabulated square which will not confuse the carpenter, which contains a uniform array and a minimum number of figures arranged to denote a maximum amount of practical information for the carpenter.

To this end I have provided a carpenter's square on one side of which are impressed

tables for ascertaining the length of common rafters and on the other side tables for the same purpose relative to hip and valley rafters. I have found that in practical work dimensions relative to all types of rafters and braces may be calculated under these two general heads, viz., common, hip and valley rafters. The tables in both cases are similarly laid out, and in referring to each for similar information the same method is followed. The only difference resides in the figures themselves which are different because of the different character and dimensions of the two general classes of rafters. Generally stated, the arrangement on one side, for example, the common rafter side, comprises a table on the blade in registration with the inch markings thereon from which the length of common rafters and analogous types of rafters may be obtained when there is given the pitch of the roof and the span in feet, the inch marks on the blade representing feet, and on the tongue a table from which similar results may be obtained when the span is in inches from 1 to 12 and in fractions of an inch. In other words, when the span is an even number of feet, the length of the rafter is obtained from the table on the blade alone. When the span includes inches less than one foot or fractions of an inch, the table on the tongue is referred to to ascertain the length sought for the span in inches and fractions thereof separately. The sum of the results obtained separately from the span in feet, inches and fractions thereof gives the total length of the rafter, and, as will be explained herein-after, these measurements for both classes of rafters take care of practically all conditions and give all the information necessary to be computed from tables for use in ordinary carpentry work.

Still another object of my invention is to provide a separable carpenter's square so that the blade and tongue may be detached and easily packed and carried. I have also aimed to materially improve and strengthen the joint between the blade and tongue so as to insure that these parts will be positively and accurately held in correct relative relation and at the same time may be easily assembled and disassembled. Referring to the drawings—

Figure 1 is a view of one side of a carpenter's square embodying my improvements, which contains tables for calcula-

tions relative to hip and valley and similar rafters;

Fig. 2 is a view of the other side of the square, containing tables for calculations 5 relative to common rafters and the like;

Fig. 3 is a face view of the elbow of the square with the markings removed to clearly illustrate the joint;

Figs. 4 and 5 are views of the joint end 10 of the blade and tongue respectively;

Fig. 6 is a longitudinal sectional view through the blade on the line 6—6 of Fig. 3;

Fig. 7 is a view of the opposite side of 15 the elbow portion from that shown in Fig. 3; and

Fig. 8 is a longitudinal sectional view through the tongue taken on the line 8—8 of Fig. 7.

The blade 11 and tongue 12 are formed 20 in separate parts detachably joined together at the elbow of the square. This joint of tenon and dovetail type, best shown in Figs. 3 to 8 inclusive, is designed to give maximum strength, as will be presently apparent. The inner end 13 of the tongue forms the tenon which is substantially the same width as the tongue except for the cutaway 25 14 on its outer side. The edges 15, 16, 17 and 18 of the tenon are beveled so that the 30 tenon will fit snugly in the groove 19 in the blade to form a dovetail connection or joint. The tenon is one-half the thickness of the body of the tongue and extends substantially across the blade. The under edge 21 35 of the tongue is undercut on a bevel throughout the width thereof and engages a correspondingly beveled face of the blade. A countersunk set-screw 22 passing centrally through the tenon is threaded into the blade 40 to securely lock the two parts together. By reason of this construction a maximum length of dovetail face is obtained, and the tongue and blade are so associated as to be positively locked and secured against relative 45 displacement during usage.

Coming now to the tabulations and other information on the square, it will be noted that the edges of the square on both sides contain graduations in inches very similar 50 to any ordinary square. In other words, the outer edge of the blade is graduated in inch markings up to 24 inches and suitably divided in fractional parts of an inch and the outer edge of the tongue is similarly divided into inch markings up to 16 inches. The inner edges of the tongue and blade are also graduated in inches as shown. Referring now to Fig. 2, which contains tables for common rafter calculations, it will be noted that the blade and tongue each contains a separate table. That on the blade is for the purpose of calculating the length 55 of the rafters and the like when the pitch and also the span in feet of the roof are known. The table on the tongue is for the

purpose of obtaining similar information when the span is in inches from 1 to 12 and fractional parts of an inch. Referring again to the table on the blade, it will be seen that from each inch mark columns of 70 figures extend crosswise of the blade on opposite sides of lines 23 and the figures of these columns are arranged between parallel lines 24 extending lengthwise of the blade. At the extreme left of these parallel lines 75 is a column of figures 25 denoting different pitches of a roof. These figures, viz., 6 to 12 inclusive, respectively designate the rise per foot in inches and I have found that invariably the pitches desired for ordinary 80 usage will be found within this range. The figures on the left hand side of the lines 23 denote feet and inches and those on the right hand side sixteenths of an inch. These figures are computed so that given the pitch 85 and span in feet of a roof they will show the exact length of a rafter. For example, if the span of a roof is seven feet and a nine inch rise is desired, the carpenter refers to the figure 9 in the column 25 and 90 traces the horizontal column in which 9 is located to the right until the vertical column under the 7" mark on the outer edge of the blade is reached, which shows 8' 9", the length of the rafter. Thus the 95 inch marks on the outer edge of the blade represent feet in connection with the calculations described. Should the span of the roof be greater than 24', the length of the blade in inches, (30' for instance), the 100 calculation may be made by referring to the 15" column and doubling the results obtained, or the same result would be obtained by adding the figures in the proper pitch level found over the 10" and 20" 105 columns.

Any measurements shorter than 1', that is relative to the span of the roof in inches or fractions thereof, are found on the table on the blade. It will be seen that this table comprises columns of figures arranged on opposite sides of lines 26 extending crosswise of the tongue and arranged between the longitudinal lines 27. Each column of figures is designated at its head in the longitudinal 110 space 28 by a figure indicative of a certain span in inches, that is, the columns are designated by 1 to 12 inch markings and fractions of an inch from $\frac{1}{8}$ to $\frac{7}{8}$ of an inch. At the extreme right of the table is a column 29 containing the different pitches arranged 115 similarly to those in the table on the blade. The method of procedure to ascertain the length of a rafter when the span and pitch is given is the same as described in connection with the table on the blade. If the span is 3" and the pitch 9", the figure 9 in the pitch column is referred to and this space followed to the left to the 3" column at 120 which will be found the dimension 4" 13, 130

which means $4\frac{1}{16}''$, the length of the rafter. If the span contains a fraction of an inch, for instance $\frac{3}{8}''$, the space 9 is followed to the left to the $\frac{3}{8}$ column at which will be found the figure 7, denoting $\frac{7}{16}''$. Taking now the example of a roof having a span of $7' 3\frac{3}{8}''$, to ascertain the length of a common or analogous rafter with a given pitch of $9''$, the length is found by applying separately the span in feet to the table on the blade and the span in inches and fractions thereof to the table on the tongue and adding together the results which will give the total length of the rafter. In other words, it has been shown that the length of the rafter for the span in feet is $8' 9''$, for the span of $3''$ a length of $4\frac{1}{16}''$ and for the fraction $\frac{3}{8}$ of an inch a length of $\frac{7}{16}''$. Adding these lengths we have $9' 2\frac{3}{8}''$, the length of the rafter. I have found this method to be most simple and practical because the table on the blade referring to the span in feet only is most frequently used and is not confused with calculations for the span given in inches and fractions, and similarly the span in inches and fractions thereof are separately treated. The whole arrangement tends to simplicity and enables the carpenter to very easily and quickly obtain the information desired.

The length of a brace or of a jack or cripple rafter may also be ascertained from the tables on the common rafter side of the square in a manner similar to that described above, since the characteristics of these rafters are the same in the matter of length as a common rafter. The end cuts, however, of jack and cripple rafters are different from the common rafter in that the plumb cut of the jack rafter and both the plumb and bevel cuts of the cripple rafter instead of being square are cut on the miter or at a 45 degree angle as is well understood in the art. It is not necessary to confuse the tables with data and computations relative to ascertaining the cuts of rafters, since when the length and pitch are known, the cuts may be correctly made by any carpenter accustomed to the use of a square of this character. For instance, the bottom or level cut is always $12''$ regardless of the rise of the roof. When the rise is known, for instance $8''$, the bottom cut will be $12''$ and the plumb cut $8''$. The distinctions between right angle and miter cuts in the various types of rafters are

well known in the art, hence a detailed explanation concerning the same is unnecessary, and especially so, because these cuts as already explained may be easily made by a carpenter after the length of the rafter has been ascertained by the aid of the tables on the square.

Referring now to Fig. 1 showing the side of the square containing calculations relative to hip and valley rafters, it will be noted that the arrangement of the tables are in every way similar to those on the common rafter side. In fact, the only difference lies in the figures themselves. Hence, a detailed explanation of these tables is not necessary for an understanding of the invention.

It is believed that my invention and its manner of use will be fully understood without further description and it should be obvious that the scope of the invention is not circumscribed by the details illustrated and described but is defined only by the following claim.

I claim:

A carpenter's square, containing thereon inch graduations on an outer edge and a table having graduations registering with the inch marks and including a column of figures indicating different roof pitches and other columns of figures in connection with the inch and pitch marks so arranged that the length of a rafter or the like may be ascertained by applying the span of a roof in feet and the pitch to the respective pitch and inch marks corresponding to the number of feet of the span, and containing also a column of figures indicating roof pitches similar to the first mentioned pitch column and columns of figures headed by marks indicating inches 1 to 12 inclusive and separate columns headed by fractions of an inch, all of which are calculated in connection with the second mentioned pitch column so that the length of a rafter or the like may be separately obtained from said inch and fraction columns when the span of the roof contains inches under 1 foot and fractions of an inch, whereby the length of a rafter of given pitch and having a roof span in feet, inches and fractions thereof will be the sum total of the lengths obtained by referring separately to the respective tables of feet, inches and fractions thereof.

GEORGE BICK.
